(57) **CLAIM**

The ornamental design for an automatic guided vehicle, as shown and described.

DESCRIPTION

FIG. 1 is a perspective view of an automatic guided vehicle showing my new design;

FIG. 2 is a front view thereof, additionally the rear view is omitted since the rear is a mirror image of the front side view;

FIG. 3 is a left side view thereof, additionally the right side view is omitted since the right side view is a mirror image of the left side view;

FIG. 4 is a top view thereof;

FIG. 5 is another perspective view thereof, wherein a top plate of the present design is raised;

FIG. 6 is another front view thereof, wherein the top plate of the present design is raised;

FIG. 7 is another left side view thereof, wherein the top plate of the present design is raised; and,

FIG. 8 is another left side view thereof, shown in environmental use, wherein the top plate of the present design is raised, an object to be conveyed is disposed on the present design on a walking surface.

A bottom view of the present design is omitted since it does not contain ornamental features. The dash lines of the object to be conveyed and the walking surface in FIG. 8 represent the environment only and form no part of the claimed design.
